CLAIM

The ornamental design for a “dehumidifier,” as shown and described.

DESCRIPTION

FIG. 1 is a perspective view of the dehumidifier in accordance with a first embodiment;

FIG. 2 is a front view of the dehumidifier in accordance with the first embodiment;

FIG. 3 is a rear view of the dehumidifier in accordance with the first embodiment;

FIG. 4 is a left side view of the dehumidifier in accordance with the first embodiment;

FIG. 5 is a right side view of the dehumidifier in accordance with the first embodiment;

FIG. 6 is a top view of the dehumidifier in accordance with the first embodiment;

FIG. 7 is a bottom view of the dehumidifier in accordance with the first embodiment;

FIG. 8 is a perspective view of the dehumidifier in accordance with a second embodiment;

FIG. 9 is a front view of the dehumidifier in accordance with the second embodiment;

FIG. 10 is a rear view of the dehumidifier in accordance with the second embodiment;

FIG. 11 is a left side view of the dehumidifier in accordance with the second embodiment;

FIG. 12 is a right side view of the dehumidifier in accordance with the second embodiment;

FIG. 13 is a top view of the dehumidifier in accordance with the second embodiment; and,

FIG. 14 is a bottom view of the dehumidifier in accordance with the second embodiment.

The broken lines illustrate portions of the article and form no part of the claimed design.

1 Claim, 10 Drawing Sheets
